CLAIM

The ornamental design for an audio pod for a communication device, as shown and described.

DESCRIPTION

FIG. 1 is a front orthographic view of an ornamental design of one embodiment of an audio pod for a communication device showing our new design.

FIG. 2 is an isometric view thereof; and,

FIG. 3 is an isometric view of an ornamental design of a second embodiment of an audio pod for a communication device showing our new design, which differs from the embodiment shown in FIGS. 1 and 2 in that the openings in the audio pod grille are of a different shape.

The broken lines shown in FIGS. 1-3 are included for the purpose of illustrating environmental elements only and form no part of the claimed design. The left side, right side, top, bottom and rear views are omitted and form no part of the claimed design.
